UNITED STATES PATENT OFFICE.

ELZA NOLIN, OF MONROE, IOWA.

DISK-SHARPENER.

1,370,350.

Specification of Letters Patent.

Patented Mar. 1, 1921.

Application filed October 28, 1919. Serial No. 333,884.

To all whom it may concern:

Be it known that I, ELZA NOLIN, a citizen of the United States, residing at Monroe, in the county of Jasper and State of Iowa, have 5 invented certain new and useful Improvements in Disk-Sharpener, of which the following is a specification.

This invention has for its object to provide an improved sharpener for the disks of 10 harrows and other farming implements embodying such features of simplicity and compactness as will adapt the sharpener to convenient transportation.

Another object is the provision of a disk 15 sharpener which may be conveniently applied to the disk supporting shaft along side of the disk and which may be conveniently oscillated upon the shaft to sharpen the circumferential edge of the disk.

With the above and other objects in view, 20 as will appear as the description proceeds, the invention comprises the various novel features of construction and arrangement of parts which will be more fully described 25 herein and set forth with particularity in the claims appended hereto.

Reference is had to the accompanying 30 drawings forming a part of this application, in which like reference characters indicate the corresponding parts throughout the several views, in which:

Figure 1 represents a fragmentary plan view of a harrow illustrating the invention applied to use, and

Fig. 2 represents a perspective view of the 35 sharpener detached.

Referring to the drawing in detail, wherein similar numerals indicate corresponding parts throughout the several views, the number 40 5 indicates the flat elongated body of the sharpener which may be conveniently and economically constructed of strap metal and is formed adjacent one terminal with a twist 6 forming the handle portion 7 lying 45 substantially at right angles to the plane of the flat portion of the body 5 for convenience in oscillating the sharpener during use.

The opposite terminal of the body is 50 formed with an aperture receiving a bolt 8 over which is pivotally mounted the looped terminal of a supporting hook 9, the latter being of such shape and size as to engage and support the sharpener in position upon the shaft 9 of a harrow or other farming 55 implement, as suggested in Fig. 1.

A substantially inverted U-shaped holder 10 having aligned rectangular openings 12 in the leg or parallel portions thereof is slidably mounted upon the body 5 and is confined between the bolt 8 and the terminal 60 twist 6. The holder 10 is prevented from turning upon the body owing to the polygonal cross sectional form of the latter and the apertures 12 are formed in such a manner as to maintain the central or web portion of the 65 member 10 in spaced relation to the body 5 to afford adequate space for the sharpening element designated generally by the numeral 14.

A screw 13 preferably provided with an 70 enlarged head for convenience of adjustment is threaded in an internally threaded aperture formed transversely through the web portion of the holder 10 and is engageable at its inner terminal with the sharpening 75 element 14 whereby the latter is rigidly clamped against the body 5 and accurately held in an adjusted position.

One terminal of the sharpening element 80 14 is formed with a beveled sharpening edge 15 so disposed as to engage and to sharpen the edge of a disk 16 when the sharpener is properly applied to the axle 9^a and oscillated and in practice I have found that the sharpening element may be formed from a flat file 85 which, owing to the quality of metal from which the files are made provides an adequate sharpening device.

In use, the hook 9 is engaged over the axle 9^a and by loosening the nut carried by the 90 bolt 8 the hook may be moved into the proper angular relation to the body 5 in order that the edge of the sharpening element 14 will be disposed in proper relation to the edge of the disk 16. The holder 10 95 is subsequently adjusted, by loosening the screw 13, to dispose the cutting edge 15 in engagement with the disk. Upon retightening the screw the several parts are frictionally held in adjusted position and by a vertical oscillatory movement of the sharpener the edge of the disk 16 is effectively sharpened.

What I claim is:

1. A disk sharpener including a body, an 105 axle engaging member carried by one terminal thereof, a holder adjustable longitudinally of the body, a longitudinally adjustable sharpening element confined between the body and holder, and means for rigidly 110

clamping the sharpening element against the body and for simultaneously securing the holder in adjusted position on the body.

2. A disk sharpener including a body, a substantially U-shaped holder slidably engaged therewith, a sharpening element confined between the web portion of the holder and the body, and means to secure the sharpening element in adjusted position.
- 10 3. A disk sharpener including a body, an axle engaging member carried by one terminal thereof, a substantially U-shaped holder slidable longitudinally of the body, a sharpening element confined between the web portion of the holder and the body, and means simultaneously securing the holder and sharpening element in adjusted position.
- 15

4. A disk sharpener including a body, an axle engaging hook adjustably connected with one terminal of the body, a handle at 20 the opposite terminal of the body, a substantially U-shaped holder movable longitudinally of the body, a sharpening element adjustable longitudinally between the web portion of the U-shaped member and the body 25 and provided with a terminal cutting edge, and a screw fitted in the web portion of the U-shaped member movable against the sharpening element to simultaneously secure the latter and U-shaped member in adjusted 30 position.

In testimony whereof, I affix my signature hereto.

ELZA NOLIN.
